UNITED STATES PATENT OFFICE

CHARLES LEVÉ, OF CANNES, FRANCE

SPORTING GUN

Application filed March 9, 1929, Serial No. 345,687, and in Belgium March 9, 1928.

The invention relates to a sporting gun having fixed barrels and a moveable block sliding on the frame of the piece.

The present invention is specific to the case of a sporting gun wherein a device for blocking the advance of the cartridges in the magazine is controlled by acting on a mechanism capable of withdrawing the cartridges from the barrel chamber. The invention provides that the ordinary extractor actuated in known manner by the percussion member (hammer) performs the function of this mechanism.

According to the invention a cartridge is withdrawn from the barrel chamber, when this cartridge has not been fired, by bringing the extractor into its operative position by means of a member actuated from the exterior by the operator and capable of acting on said device.

By way of example, and not limiting, the accompanying drawings show an embodiment of the invention, which includes various details comprised in the arrangement shown.

Figure 1 shows an elevation of the loading and extracting mechanism;

Figure 2 shows a plan view thereof;

Figure 3 shows a front view thereof; and

Figures 4 to 6 are views similar to Figures 1 to 3 but showing the gun in position for automatic loading.

The cartridges are placed in the barrel either manually or automatically by means of independent loaders such as 2a adapted to move in the magazine 2m integral with the frame or body. For this purpose the loaders such as 2a are pivoted at 21a on the body. During the automatic loading of the gun the loader pivots under the action of a spring 2t and carries the cartridge (not shown) which it supports opposite the barrel chamber. As a result of the forward movement of movable block 3, during closure of the arm, the cartridge is released from the resilient jaws 2p and forced into the barrel.

Where the loader, instead of being formed by a blade, is made of a housing containing several cartridges, these latter are carried automatically in front of the barrel cham-

ber by the fact that the loader comprises a movable bottom which is actuated by another spring which bears on the same end of the loader.

The retention of the loader 2a in the bottom or end of the magazine is assured by the action of a shoulder 2d pivoted on the body and bearing on a shoulder 2u of the loader. The loader is released by actuating the plug 4a.

When this plug is in its inoperative position (see Figs. 1 to 3) the operation is as follows: The block 3 of the gun being drawn back, the head 5b of extractor 5 is retained in its inoperative position against the force of a spring 5r, while the arm 5a of a lever 5g bears against the lower surface of the extractor 5 through the action of the spring 5v (position shown in full lines). After having inserted the cartridges manually into the barrel the gun is closed by pushing block 3 forwardly.

When firing the hammer, not shown, exerts action against a projection 5s of the extractor and forces the latter into engagement with the cartridge in the barrel. The arm 5a is released as a result of the extractor being removed and pivots under the action of spring 5v about its axis 5p so as to come into position behind the tail of the extractor (dotted lines) and hold the latter engaged.

During the opening of the gun the positions of extractor 5 and of arm 5g remain unchanged, except at the end thereof; at the end of the opening a spur 2v integral with the body of the gun exerts action under a ramp or inclined plane 5h of arm 5g and forces the latter to pivot against the action of its spring 5v and to assume the position shown in full lines and release the extractor.

If, when the arm is locked in its closed position, the marksman desired to replace the unfired cartridge then in the barrel, he causes the plug 4a to pivot about its axis 41a and in the direction of the arrow X.

A ramp 4t provided on the plug 4a exerts action on a corresponding ramp 5t provided on the extractor and puts the latter in engagement with the cartridge in the barrel;

this extractor is locked in this position by the release of the arm 5a, which occupies the position shown in dotted lines.

At the same time an inclined surface 4m provided on the axis 41a of the plug acts on an element 41b integral with a rod 4b sliding in the block and forces the latter downwardly against the action of the spring 4r.

10 The respective position of these different elements does not change during the greater part of the opening of the breech, but at the end of this opening the rod 4b acts against a rod 2n movable in the body of the 15 arm and pushes it downwardly as well as the member 2s which is integral therewith. This member 2s is provided with an inclined opening 2r into which penetrates a spur or lug 2h fitted on the pivoting lug 2d. The 20 lowering of member 2s causes the pivoting of arm 2d about its axis and thus the release thereof from the shoulder 2u of loader 2a. The latter assumes the position shown in Fig. 4.

25 The end of the opening of the breech likewise determines the release of the extractor through the action of the lug 2v. On returning to its initial position under the action of its spring 5r the extractor 5 acts by 30 its shoulder 5t against the ramp 4t of plug 4a and forces the latter to resume its initial inoperative position.

The cartridge withdrawn from the barrel having been ejected, it is sufficient to move 35 the block forward again to force the cartridge of the loader into the barrel.

I claim:

1. A gun having a magazine for cartridges, means permitting automatic or 40 single fire, said means permitting the blocking of the advancing of the cartridges in said magazine, mechanism for withdrawing the cartridges from the chamber of the barrel controlling said means, and said mechanism having associated therewith an extractor controlled by the percussion apparatus of the gun.

2. A gun having a magazine for cartridges, means permitting automatic or single fire, said means permitting the blocking of the advancing of the cartridges in said magazine, mechanism for withdrawing the cartridges from the chamber of the barrel controlling said means, said mechanism having associated therewith an extractor controlled by the percussion apparatus of the gun, said extractor being also controllable by a button actuated by the shooter and provided with a cam acting on a head of the extractor.

3. A gun having a magazine for cartridges, means permitting automatic or single fire, said means permitting the blocking of the advancing of the cartridges in said magazine, mechanism for withdrawing the

cartridges from the chamber of the barrel controlling said means, said mechanism having associated therewith an extractor controlled by the percussion apparatus of the gun, said extractor being also controllable by a button actuated by the shooter and provided with a cam acting on a head of the extractor, this button being further provided with a surface acting on a lever pivoted upon the breech and able of bolting the extractor in its operating position.

4. A gun having a magazine for cartridges, means permitting automatic or single fire, said means permitting the blocking of the advancing of the cartridges in said magazine, mechanism for withdrawing the cartridges from the chamber of the barrel controlling said means, said mechanism having associated therewith an extractor controlled by the percussion apparatus of the gun, said extractor being also controllable by a button actuated by the shooter and provided with a cam acting on a head of the extractor, said button being further provided with a surface acting on a lever pivoted upon the breech and capable of bolting the extractor in its operating position and with another surface acting on a movable abutment controlling the loader.

5. A gun having a magazine for cartridges, means permitting automatic or single fire, said means permitting the blocking of the advancing of the cartridges in said magazine, mechanism for withdrawing the cartridges from the chamber of the barrel controlling said means, said mechanism having associated therewith an extractor controlled by the percussion apparatus of the gun, said extractor being also controllable by a button actuated by the shooter and provided with a cam acting on a head of the extractor, said button being further provided with a surface acting on a lever pivoted upon the breech and capable of bolting the extractor in its operating position, the unbolting of the extractor and its return to its nonoperating position being obtained by the opening of the gun after the extraction of the cartridge.

6. A gun having a magazine for cartridges, means permitting automatic or single fire, said means permitting the blocking of the advancing of the cartridges in said magazine, mechanism for withdrawing the cartridges from the chamber of the barrel controlling said means, said mechanism having associated therewith an extractor controlled by the percussion apparatus of the gun, said extractor being also controllable by a button actuated by the shooter and provided with a cam acting on a head of the extractor, this button being further provided with a surface acting on a lever pivoted upon the breech and capable of bolting the extractor in its operating position, the unbolt-

ing of the extractor and its return to its nonoperating position being obtained by the opening of the gun after the extraction of the cartridge, a declivity of the said bolting lever cooperating therefor with a fixed hook of the carcass.

5 7. A gun having a magazine for cartridges, means permitting automatic or single fire, said means permitting the blocking of the advancing of the cartridges in said magazine, mechanism for withdrawing the cartridges from the chamber of the barrel controlling said means, a loader for the magazine formed by a lever pivoted upon the carcass and acted upon by a spring, 10 a piece moved by an element controllable by the shooter being capable of bolting this loader.

15 8. A gun having a magazine for cartridges, means permitting automatic or single fire, said means permitting the blocking of the advancing of the cartridges in said magazine, mechanism for withdrawing the cartridges from the chamber of the barrel controlling said means, a loader for the magazine formed by a lever pivoted upon the carcass and acted upon by a spring, 20 a piece moved by an element controllable by the shooter being capable of bolting this loader comprising elastic tongs for maintaining the cartridges.

25 In testimony whereof I have affixed my signature.

CHARLES LEVÉ.
